UNITED STATES PATENT OFFICE.

DAVID C. COBLE, OF ELIZABETHTOWN, PENNSYLVANIA.

FOLDING LAWN-SWING.

SPECIFICATION forming part of Letters Patent No. 697,133, dated April 8, 1902

Application filed October 18, 1901. Serial No. 79,129. (No model.)

To all whom it may concern:

Be it known that I, DAVID C. COBLE, a citizen of the United States, residing at Elizabethtown, in the county of Lancaster and State of 5 Pennsylvania, have invented a new and useful Folding Lawn-Swing, of which the following is a specification.

This invention relates to folding lawn-swing; and the object of the same is to provide 10 simple and effective jointed means in the frame which will permit the same to be compactly closed to reduce the space of occupancy for storage, transportation, and other purposes without removing any bolts, screws, 15 or loosening nuts and formed either of metal, wood, or a composition of both of these materials, the suspending means being readily detachable and attachable and the seat-platform, to which said latter means are connected, 20 having the seat devices foldable over thereon to materially reduce the normal extent of the same.

The invention consists in the construction and arrangement of the several parts, which 25 will be more fully hereinafter described and claimed.

In the drawings, Figure 1 is a perspective view of a swing embodying the features of the invention and shown arranged for use. 30 Fig. 2 is a perspective view of the frame shown folded in compact form. Fig. 3 is a perspective view of a suspended platform for supporting the seats and showing the latter folded over thereon. Fig. 4 is a detail perspective view of a connecting-bracket for a portion of the parts. Fig. 5 is a detail perspective view of a fulcrum device for some of the parts. Fig. 6 is a detail perspective view showing the joint and connection for the one 35 set of end braces for the upper part of the frame. Fig. 7 is detail elevation of the joint and means of connection for the opposite sets of side braces for the frame.

Similar numerals of reference are employed 45 to indicate corresponding parts in the several views.

The numeral 1 designates uprights or standards, which are disposed at an outward angle of inclination when in normal supporting position and are adapted to be formed of angle-iron or other metal, wood, or other material. 50 By forming the said standards or uprights

with a cross-sectional angular contour means for attaching the ends of the several braces is provided. To the upper portions of the 55 opposite pairs of uprights the lower ends of end braces 2 are pivotally connected and are crossed near their upper extremities and connected by a pivot 3, and on opposite side of the joint thus formed keeper-disks 4 are held. 60 To the upper ends of the said braces 2, by means of pivots 5, are auxiliary braces 6, which are also pivotally connected to the upper ends of the uprights. The inner ends of the said auxiliary braces extend freely in- 65 ward beyond the points of their pivotal connection with the said braces 2 for depression between the upper portions of the disks and form a lock to limit the spread of the uprights in a transverse direction and also to 70 reinforce the braces 2 by taking up a part of the strain that is brought to bear thereon. As clearly shown by Fig. 6, the inner ends 75 of the auxiliary braces are cut off at an angle of inclination to fit down upon the edges of the braces 2 above the crossed joint of the latter, the angle of the said ends of the braces 6 corresponding to the angle of the braces 2 or the edges of the latter when said braces 2 are opened to their full extent. 80

Extending longitudinally of each side of the uprights, at the upper portions of the latter, is a jointed suspending-bar comprising two sections 7 and 8, which are each pivoted to an upright at a point between the planes 85 of the pivots of the braces 2 and 6, the pivots of the said sections being in longitudinal alinement, the greater portions of the sections being located inwardly from their pivots, and each has a notch 9 in the upper edge 90 portion of the outer end. The inner end of the section 7 is pivoted to the section 8, this pivotal arrangement of the two sections being such that their inner ends will overlap when longitudinally disposed, the inner free 95 end of the section 8 having a headed stud 10 to enter a notch in the upper edge of the section 7 to prevent the two sections from lowering below a horizontal plane. The outer projecting ends of the jointed suspending- 100 bars suspend the swinging means below, and hence considerable weight is brought to bear on said ends, and it is necessary to retain them in positive position when in distended

bracing condition, as shown by Fig. 1, and for this purpose a pair of crossed retaining-braces 11 are employed with each jointed suspending-bar and have their lower ends pivotally attached to the uprights and their upper ends respectively attached by pivots to the sections 7 and 8 on opposite sides of the point of pivotal connection of the two sections. These retaining-braces have considerable length to give them increased bracing action and at their point of crossing are unconnected, so that they will slip easily on each other in opening or closing the same.

The outer notches 9 of the sections 7 and 8 are provided for the removable engagement therewith of headed studs 12 on the outer sides of the upper ends of hanger-bars 13, which extend downwardly and have their lower ends pivotally attached to the outer side portions of the opposite ends of angular side bars 14, having transverse cross-slats 15 therein to produce a sustaining-platform 16, which also serves as a foot-platform for the swing. By constructing the bars 14 angular in cross-section a reliable seating means for the opposite ends of the slats 15 is provided, and from a structural standpoint a simple and convenient method of forming the platform results. The hanger-bars 13 are first curved inwardly and then outwardly to give them a positive clearance, and the lower extremities are substantially straight. Two slatted seats 17 are disposed on the platform, though it is obvious in some instances this number might be varied, each seat comprising a base resting portion, with a back continuing therefrom and side arms. To the rear side of the back portion of each seat a pair of brackets 18 are secured, one at each side, and, as clearly shown by Fig. 4, each bracket comprises a pair of arms 19 terminally secured to the back portion of the seat and converging to a rear central head 20, carrying a fulcrum 21 to serve as a pivot connection for the lower portion of each hanger-bar in relation to the back portion of opposite sides of the seat and permit each seat to sway in an upright position in conformity with the movement of the hanger-bars connected thereto. The inner portion of the base-rest of each seat has pendent supports 22, secured to opposite sides thereof by a pivotal connecting device 23, (shown in detail by Fig. 5,) the lower ends of the said pendent supports being also pivoted to the outer sides of the angular side bars 14 of the platform 16, and thus the seats and platform will always be permitted to maintain a substantially horizontal position or a normal disposition.

60 The frame constructed as set forth when spread out, as shown by Fig. 1, will provide an efficient means for supporting a swinging means, and may be folded, as shown by Fig. 2, into compact form for storage or transportation, and in pursuing this folding operation of the frame no fastening means or bolts are removed or loosened, the uprights being sim-

ply pushed toward each other. In rearranging the frame for supporting service the uprights are drawn outwardly from each other 70 and the folding connecting parts will assume the position shown by Fig. 1 without manual adjustment or disposition. As shown by Fig. 3, the hanger-bars, platform, and seats may also be reduced to compact form by throwing 75 the seats over on the platform and infolding the hanger-bars in reverse position.

The complete folding organization set forth is as an entirety preferred by reason of the convenience in packing, storing, transporting, 80 and setting up in operative position; but it is obvious that at times other swinging means may be used in connection with the frame, having hangers that can be separately attached to the suspending-bars. 85

The pivotal connecting devices 23 comprise a base-support 24, which is secured to the under side of the base-rest of the seat, and an upstanding head 25 at the outer end of said support, a fulcrum 26 projecting from said head for engagement with the upper end of the pendent support 22 in each instance. Both the brackets and the pivotal devices can be easily attached, and the device as an entirety presents a strong and durable swing 95 for lawn purposes, though adapted to be used elsewhere, as may be desired.

Having thus described the invention, what is claimed as new is—

1. A swing comprising a frame having uprights, upper end braces pivotally connected to said uprights, auxiliary braces also pivoted to said uprights and to the ends of said first-named braces, suspending-bars pivotally connected to the opposite side portions of the frame, and swinging means connected to said suspending-bars. 100

2. A swing comprising a frame having uprights, folding braces connecting the uprights at the upper portion of opposite ends of the frame, jointed suspending-bars at the upper opposite side portions of the frame pivotally connected to the uprights, retaining-braces pivotally attached to the suspending-bars and uprights, and swinging means having hangers terminally connected to the outer ends of the suspending-bars. 110 115

3. A swing comprising a frame having uprights, braces pivotally connected to said uprights, auxiliary braces also pivoted to said uprights and to the ends of said first-named braces, and provided with beveled ends adapted to bear on and engage the upper edge portions of the first-named braces, suspending-bars pivotally connected to the opposite side portions of the frame, and swinging means connected to said suspending-bars. 120 125

4. A swing comprising a frame having uprights, folding braces in sets at the upper end portions of the frame, jointed suspending-bars pivotally attached to the uprights at points between the points of attachment of said folding braces, and swinging devices attached to the suspending-bars. 130

5. A swing comprising uprights, the jointed suspending-bars arranged at opposite sides of the swing and composed of sections pivoted between their ends to the uprights and pivotally connected at their inner ends, said sections also having their inner portions interlocked, the braces extending from the uprights to the sections and connected with the latter between the said uprights, and swing-
10 ing devices suspended from the outer ends of the sections, substantially as described.

6. A swing comprising a frame having uprights, upper end braces pivotally connected to the uprights and crossing each other, the points of crossing of the said braces being secured by pivots, a retaining means applied to the crossed pivoted portions of the said braces, auxiliary braces also pivoted to the uprights and to the upper ends of the first-named braces and having their inner ends angularly formed to bear on the upper edge portions of the latter braces, suspending devices also foldingly constructed and disposed on opposite sides of the frame, and a swinging means attached to said suspending devices.

25 7. A swing comprising a frame having uprights, folding braces at the upper end por-

tions of the frame, jointed suspending-bars pivotally attached to the upper opposite sides of the frame, the one section of each bar having a stud to removably engage a notch in the other, retaining-braces having their lower ends pivotally attached to the uprights and their upper ends similarly connected to the sections of the suspending-bars on opposite sides of the joint of the latter, the upper portions of the retaining-braces being crossed, and swing means attached to said suspending-bars.

8. A swing comprising uprights, jointed suspending-bars composed of sections pivoted between their ends to the uprights and extending inward and outward therefrom, swing devices suspended from the outer portions of the sections, and braces connecting the inner portions of the sections with the uprights, substantially as described.

In testimony that I claim the foregoing as my own I have hereto affixed my signature in the presence of two witnesses.
